WILLIAM K. BASSFORD, OF PERTH AMBOY, NEW JERSEY.

CARBURETER.

946,632.

Specification of Letters Patent. Patented Jan. 18, 1910.

Application filed February 19, 1909. Serial No. 478,804.

To all whom it may concern:

Be it known that I, WILLIAM K. BASSFORD, a citizen of the United States of America, and resident of Perth Amboy, in the county of Middlesex and State of New Jersey, have invented certain new and useful Improvements in Carbureters, of which the following is a specification.

My present invention relates to a carbureter intended especially for use on automobiles and motor boats, and for other uses to which it is adapted.

The main object of the invention is to dispense with all manually adjusting devices for regulating the supply of either the gasoline or air, and to do this without increasing the complexity of the construction.

Without defining the scopes of the invention which are attended to in the claim hereinafter annexed, my general conception comprises a vane which is located in the air current, and is movable to and fro according to the speed of the air, for automatically adjusting the effective size of the gasoline port, in the side of a tube, inside of which slides a cylindrical valve which is attached to said vane. When the speed of the motor is too great, the said valve automatically closes said port. The carbureter has a free passage at all times, for the air, and I provide means for adjusting the size of this passage, said means consisting of interchangeable perforated partitions, with holes of different sizes.

The device for illustrating my conception is set forth in the accompanying drawing.

Figure 1 is a vertical sectional view of the device, while Fig. 2 is a plan of the upper portion of a part of the device for showing the air passage.

I will now describe what is shown in the drawing.

A is a casing, the upper portion of which constitutes the air chamber, in which is located a vane J, movable downward by the pressure of the moving air, while a retractile spring T is provided for lifting the vane J, when the speed of the air diminishes. The spring T is conveniently located on the stem V, to which the vane J is attached, and which passes through a bearing K, on the top of the casing A, said spring being between the bearing K and the ad-

justable nut U, on the stem. A valve W projects below the vane J, and enters the gasoline nozzle E for varying the admission of the gasoline through the gasoline port H, in the nozzle E. Varying speeds of air through the air chamber cause varying movements of the vane J, and consequently varying supplies of the gasoline automatically.

D represents a device for forming a stricture of the air passage. The restricted opening is the annular space X around the gasoline nozzle E. I provide other stricture devices of different sizes, any one of which may be inserted, according to the conditions under which the carbureter is to work.

R is the throttle located in the pipe F for supplying the motor.

G represents the permanent air passage around the vane J, whereby the air passage is never closed.

The other details shown, but having no direct bearing on the novelty, are the float chamber L, a float M, therein, a lever N for the ball valve O, a gasoline inlet P, and a primer Q. S is the pet cock for cleaning the float chamber. As these details are old, their operation need not be described.

The invention may be modified, in so far as the modifications fall under the claim.

The detailed operation of the means for regulating the supply of gasoline will now be set forth.

The throttle R is opened, and the air commences at once to pass through the opening at the top of the carbureter at each side of the bearing K, and to enter the air chamber at the upper portion of the casing A. It then passes through the annular space around the vane J, then through the restricted passage at X, and then into the engine by passing through the throttle port around the throttle valve R. In passing by the port H in the tubular gasoline nozzle E, it draws out, by suction, gasoline, from the tank L, in the form of gasoline vapor. I purposely make the port H, rectangular, as shown, so that if the valve W is half way down, one half as much gasoline will be drawn out as if fully open, and similarly, for all positions of the valve W, proportionate amounts of vapor will be drawn out. As the speed of the air increases, the vane J will continue to descend, and when the speed

is greater than desired, the port H will be completely closed, thus automatically, stopping the motor, or engine.

I claim as my invention,

- 5 In a carbureter, the combination of a casting forming an air chamber, a tubular gasoline nozzle, extending into said chamber, and having a rectangular port running along the side of the nozzle, a valve extending into said nozzle, for covering said port

more and more in direct proportion to its distance in the nozzle, and means governed by the air passing through said chamber for adjusting the valve along the length of said port.

WILLIAM K. BASSFORD.
